Primary Examiner — Derrick Holland*Assistant Examiner* — Lauren Calve(74) *Attorney, Agent, or Firm* — Leason Ellis LLP(57) **CLAIM**

The ornamental design for a shirt and tie arranged in a box, as shown and described.

DESCRIPTION

FIG. 1 is a front elevation view of a shirt and tie arranged in a box showing my new design;

FIG. 2 is a bottom plan view thereof;

FIG. 3 is a top plan view thereof;

FIG. 4 is a rear elevation view thereof; and,

FIG. 5 is a front elevation view of a shirt tie arranged in a box according to a second embodiment.

The broken line showing of a shirt and bow tie arranged in a box represents unclaimed subject matter and forms no part of the claimed design. All sides not shown form no part of the claimed design.
